UNITED STATES PATENT OFFICE

EDWIN LUNDGREN, OF FREDERICK, MARYLAND, ASSIGNOR TO INTERNATIONAL COMBUSTION ENGINEERING CORPORATION, OF NEW YORK, N. Y., A CORPORATION OF DELAWARE

BOILER FURNACE

Application filed December 8, 1925. Serial No. 73,991.

This invention relates to boiler-furnaces, and is especially useful where the fuel is burned in suspension, as, for example, pulverized coal. I employ the term "boiler-furnace" as indicating a boiler installation; the furnace of which is primarily defined by the boiler itself, whereby the evaporating elements are subjected to radiant heat.

It is one of the objects of my invention to utilize the radiant heat, or the radiation, to a maximum extent, and to provide a boiler-furnace in which the flame can be so burned as to secure approximately the theoretical maximum flame radiation.

Another object of the invention is to simplify the boiler in some of its features, and to provide an installation which, in its overall dimensions, both as to height and ground area, is very small, as compared to what is today required in standard practice for producing the same, or anywhere near the same, quantity of steam.

It is another object of the invention to provide a boiler-furnace so constructed and arranged that it is possible to locate a superheater so as to obtain any degree of superheat desired.

It is still a further object of the invention to make it possible to fire the fuel with low injection pressure, and low air pressure, whereby the power requirements for operation are materially reduced.

My invention also contemplates a construction by virtue of which practically standard units may be employed, in consequence of which it is possible to construct boiler-furnaces of various capacities, merely by increasing or decreasing the number of units employed.

A further object of the invention is to so burn the fuel that the boiler-furnace of my invention can be effectively used.

How the foregoing, together with such other objects as may hereinafter appear, or are incident to my invention, are obtained, is illustrated in the preferred form in the accompanying drawings, wherein—

Fig. 1 is a vertical section through a boiler-furnace embodying my improvements.

Fig. 2 is a section taken on the line 2—2 of Fig. 1, and

Fig. 3 is a section taken on the line 3—3 of Fig. 1.

Referring now to the drawings, the reference character A denotes the boiler combustion chamber considered as a whole. This combustion chamber is largely formed by boiler tubes subject to radiant heat, and by certain refractory wall portions to be described. The combustion space of the furnace at the sides is defined by two water walls, a, a, such water walls consisting of a plurality of tubes 7 slightly inclined from the horizontal, and arranged in a vertical row. These tubes are provided on opposite sides with longitudinally extending fins 8, which fins are preferably welded to the tubes, and cooperate with the tubes to constitute, in effect, a practically continuous metallic wall. At the rear, the tubes of the side water walls are connected into the headers 9, 9, and at the front they are connected into the headers 10, 10. The headers 10, 10, are connected into the drum 11 by upcomers 12, 12. The headers 9, 9, are connected by downcomers 13, 13, to the drum 11, whereby circulation takes place downwardly through said downcomers into the headers 9, 9; thence through the tubes 7 to the headers 10, 10, and through the connections 12, 12, back to the drum. The interior of the combustion chamber is divided into vertical compartments b, c, d, e, by the water walls f. Each of these water walls comprises tubes 7^a inclined slightly from the horizontal, and arranged in a vertical row, terminating short of the arch 14 of the chamber, and also well above the ash pit 15 of the chamber. These tubes 7^a are provided with fins 8 after the same fashion as the tubes 7. The rear ends of the tubes of each of these walls f connect into a header 16, and the front ends of the tubes are connected into the headers 17. The headers 16 are connected by downcomers 18 with the drum 11, and the headers 17 are connected by upcomers 19 to the drum 11.

A hollow wall portion 20 depends from the arch 14 to the lower end of the water walls f, this baffle being divided to permit

of the passage therethrough of the water walls *f*.

Refractory walls form the ash pit, and surround the combustion space bridging the gaps between the various headers described. In fact, these headers are set into these refractory walls, as will be clear on inspection of the drawings.

Located above the ash pit 15, and well beneath the lower end of the baffle 20, and the lower ends of the water walls *f*, is a water screen *g* which is composed of tubes 21, so spaced apart that the gravitating refuse particles can freely pass therebetween into the ash pit. At their rear ends the tubes 21 connect into the header 22, and at their front ends they connect into the header 23. The header 22 is supplied with water from the headers 16 by means of the connections 24, and the connections 25 constitute upcomers from the header 23 into the headers 17. Thus, the water screen is in substantially the same circulation as water walls *f*.

By the arrangement of parts described, the interior of the combustion chamber is divided into the vertical compartments *b*, *c*, *d*, *e*, by the water walls *f*. The space is divided into a sort of a U-shape by the baffle wall 20.

The pulverized fuel is admitted into the top of the combustion chamber by means of burners 26, of which there is one located above each vertical compartment described. These burners are flattened so as to deliver a thin sheet of fuel mixed with carrying air, that is to say, mixed with only a portion of the air required for combustion. There is, thus, a fuel and flame stream for each vertical compartment, the fuel and flame stream proceeding downwardly in advance of the wall 20 around the lower end thereof, and between such lower end and the water screen *g*, and thence up through the vertical compartments to the off-take 27 of the installation. The width of the vertical compartments is preferably in the neighborhood of three feet, and the width of the fuel and flame stream in each compartment is approximately two feet, by virtue of which I obtain the maximum radiation from the flame, and utilize this maximum radiation most effectively because the tubes which define these passageways are subjected to the maximum radiant heat thus obtained, and, therefore, transmit it at a maximum rate. Consequently, I can produce a given quantity of steam, with but a fraction of the evaporating area now required for this purpose, and can develop this capacity enormously.

By virtue of the rapid absorption of heat by the tubes, there will be a tendency to unduly lower flame temperature, to overcome which the balance of the air required for combustion is delivered in highly preheated form, so as to increase the temperature head. I ac-

complish this by providing a casing 28 over the front wall of the combustion chamber, and a casing 29 in back of the baffle 20. Air is supplied to these casings from an air heater 30 located in the off-take 27. Air enters into the combustion space from the casings 28 and 29 through the inlets 31 and 32. There are two rows of these inlets 31 in the front wall for each vertical compartment, and there are two rows of these inlets 32 through the baffle 20 for each vertical compartment. The air admitted through these inlets preferably, under pressure, produces violent agitation and turbulent combustion, and, by virtue of this and the high degree of preheat of the air, combustion is completed without appreciable loss in combustibles. The flame is also short, and combustion is practically completed before the flames turn around the lower end of the baffle 20. The gases of combustion rise through the compartments to the rear of the baffle 20 to the off-take, and I locate superheater elements 33 in the compartments to the rear of the baffle 20 at about the level of the lower end of the baffle, and I locate economizer elements 34, if desired, in the top portion of the space behind the baffle wall 20. It will be seen that the superheater elements may be located at any level with convenience, and that, in consequence thereof, any desired degree of superheat may be obtained.

I prefer that the total evaporating surface should be such that the gases leave the economizer at a much higher temperature than heretofore contemplated in standard practice, to the end that the high degree of heat desired for the combustion air may be absorbed in the air heater. Obviously, the casing 29, being subjected to the heat of the waste gases, will serve to impart additional heat to the air.

The function of the screen is to prevent slagging of the refuse particles, the screen acting to cool such refuse particles while they are in transit to the point of deposit in the ash pit to a condition in which the particles are no longer molten, in consequence of which they remain in individual form readily removable.

No slagging difficulties will be encountered elsewhere within the combustion chamber by virtue of the action of the tubes.

It will be observed that the installation is essentially a down-draft one, in consequence of which the injection pressure of the fuel and air may be relatively lower than would be otherwise required. This effects quite a saving in the power requirements which would otherwise be considerably greater for reasons which will be fully appreciated by those skilled in the art.

What I claim is:—

1. In combination, a pulverized fuel burning combustion chamber, and a plurality of walls dividing the interior into narrow flame-

ways, said walls being composed of finned boiler tubes subject to radiant heat, said tubes being spaced so that the fins substantially abut.

5 2. In combination, a pulverized fuel burning combustion chamber, and a plurality of walls dividing the interior into narrow flame-ways, said walls being composed of boiler tubes extending substantially for the full
10 height of the combustion chamber, together with a depending baffle transverse to the said walls and cooperating therewith to make the flame-ways of approximately U-shape, and heat absorbing elements in a vertical leg portion of a flame-way, said means comprising serially arranged superheater and economizer elements.

In testimony whereof I have hereunto signed my name.

EDWIN LUNDGREN.
